UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,090,458.

Specification of Letters Patent. Patented Mar. 17, 1914.

Application filed May 1, 1909. Serial No. 493,326.

To all whom it may concern:

Be it known that I, FRANK DUTCHER, a citizen of the United States, residing at Versailles, in the county of Allegheny and State of Pennsylvania, have invented certain new and useful Improvements in Railway Signal-Torpedoes, of which the following is a specification, reference being had therein to the accompanying drawing.

10 This invention relates to improvements in railway signal torpedoes, and pertains to that type of torpedo in which the case is constructed of a non-metallic material for the purpose of preventing the flying of particles of metal and the consequent injury to persons who may happen to be in the path of any of these flying pieces.

20 The present improvement relates primarily to, first, the manner of connecting the rail-engaging strap to the torpedo case; second, the water-proofing of the ends of the case which contains the explosive substance.

In the accompanying drawing—Figure 1 is a longitudinal central sectional view of a 25 torpedo embodying the present improvements, it being shown attached to a railroad rail. Fig. 2 is a central transverse sectional view. Fig. 3 is a perspective view of the completed torpedo and rail-engaging strap attached. Fig. 4 is a perspective view of the 30 torpedo partially completed and before the strap is attached thereto. Fig. 5 is an exaggerated sectional view through a portion of the base of the torpedo case, showing the 35 folds or layers of which the casing is composed and their position after being pierced to receive the rail-engaging strap.

In carrying out the present improvement 40 the fibrous case 1, is composed of paper. This case is a section of a paper tube, the tube formed by the wrapping or winding of a sheet of paper in the manner in which paper tubes are usually formed. The tube in this instance, of course, is made of the 45 contour of the casing 1, and is made of a convenient length from which the sections which form the case 1 are cut. Since this manner of forming the case does not form any part of the present improvement, only 50 so much of the method or manner of constructing it is shown and described as is necessary for an understanding of the invention. The section or case 1, is subjected to suitable treatment of a suitable water-proof-

ing compound before the explosive material 55 is placed within the case.

The explosive mixture 2, is first formed into a plastic mass and then placed within the case 1. Preferably the explosive mixture is permitted to dry, after which the rail-engaging strap 3 is attached and the torpedo completed.

One of the present improvements consists in the manner of attaching the rail-engaging strap 3 to the torpedo case, which comprises 65 the longitudinal piercing of the base of the case 1, as shown at 4, with any suitable thin elongated instrument. The rail-engaging strap 3 is then inserted through the opening 4 into the position here shown. In Fig. 3 70 an exaggerated sectional view is given of the wall of the case 1, from which it will be seen that the case is composed of a number of layers 5 and that the opening 4 is formed by the piercing instrument passing between 75 the layers and separating them sufficiently to receive the strap 3. This opening 4 extends in a direction longitudinal of the case and the layers of which the case is formed are not pierced but simply separated. The 80 case having been filled with the explosive mixture it is necessary to close the ends of the case and to thereby protect the explosive mixture from dampness and moisture. It is also found that under the action of dampness; water, and the handling to which the 85 torpedoes are subjected in the hands of the railway employees, tends to slightly open up or separate the layers 5 at the ends of the case. When so separated the torpedoes will 90 be comparatively useless in the presence of water.

Another object of the present improvement is the closing of the ends of the case in a manner to prevent the moisture 95 or water entering the explosive mixture or between the layers of the sheet of which the case is formed and to also prevent the opening up or separating of the layers at the ends of the case by reason of handling of the torpedoes by the railway employees. To accomplish this after the strap 3 is passed through the opening 4, and the end of the case is subjected to a coating of water-proofing compound which 100 forms a closing sheet or layer 6, as shown in Figs. 1 and 3. This water-proofing sheet is placed on the ends of the case and also com-

pletely incloses the ends of the explosive mixture 2, as shown in Figs. 1 and 3, and also spreads out or sufficiently engages the strap 3, as shown at 7, to form, to some extent, a cementing of the strap to prevent its endwise movement through the base of the case, and serve to hold it in position. This water-proofing compound preferably consists of bees-wax, resin and plaster of Paris, 10 which has the combined effect of forming a water-proof coating, sheet or closure for the ends of the case, and a cementing action.

To prevent the torpedo slipping on the tread of the railroad rail 8 when struck by 15 the wheel of an approaching engine, the outer face of the base of the case is provided with a coating of sand or other similar granular material 9, which will be attached thereto preferably by using shellac. This 20 sand coating is preferably applied after the

strap is attached, though it may be applied before the strap is attached.

Having thus described my invention what I claim and desire to be secured by Letters Patent is:

25 A railway torpedo comprising an open-ended single wall tube formed from a wrapped and cemented sheet of paper, the wall of the tube having an open-ended strap receiving opening formed between the wrapped layers of the wall, and a rail-engaging strap passing through said opening, whereby a cheap and effective torpedo carrying a rail attaching strap is produced.

In testimony whereof I affix my signature 25 in presence of two witnesses.

FRANK DUTCHER.
